UNITED STATES PATENT OFFICE.

OCTAVE PAYZANT, OF NEW YORK, N. Y.

FOUNTAIN LETTERING-PEN.

SPECIFICATION forming part of Letters Patent No. 758,381, dated April 26, 1904.

Application filed September 14, 1903. Serial No. 173,131. (No model.)

To all whom it may concern:

Be it known that I, OCTAVE PAYZANT, a citizen of the United States, residing in New York, in the county of New York and State of New York, have invented certain new and useful improvements in Fountain Lettering-Pens, of which the following is a specification.

My invention relates to improvements in lettering or marking pens, and is intended principally for drafting use. It is designed to hold a large volume of ink and to make wide lines of uniform width in any direction.

It consists of two principal parts constructed of brass or other suitable metal. The first part is the pen proper, which has heavy rigid nibs with a beveled circular marking-point. The second part is the ink-holding device, constructed of sheet metal suitably shaped and attached to the under side of the first part.

In the accompanying drawings, which are enlarged for clearer illustration, Figure 1 shows a top view of my pen. Figs. 2 and 3 show side views. Fig. 4 shows a bottom view.

Similar letters refer to similar parts throughout the several views.

The pen-body is indicated by A, and the ink-holder by B.

c is a thumb-screw which clamps the lower end of the ink-holder B to the pen-body A.

d is the hinge connecting the ink-holder B to the pen-body A.

e is the flat beveled circular marking-surface.

f is a transverse slot across the bottom side of the pen-body A, into which the lower edge of the ink-holder B fits to prevent leakage.

The pen-body A is formed from a straight piece of metal rectangular in section. It has a large central opening tapering into a fine slit between the nibs. Each nib ends in a semicircular point, giving the pen a circular marking-surface, thus producing lines of a width equal to the diameter of the marking-point in whatever direction in which the pen

is moved. The marking-surface is beveled to an angle of forty-five degrees in order to lie flat on the surface of the paper when the pen is held in the ordinary position for writing. The nibs are practically rigid, so that unequal

pressure will not produce any inequality in the width of lines drawn.

The sides of the ink-holder B fit closely to the edges of the pen-body A, and at the lower end of B both sides rise sufficiently high above the pen-body to allow the thumb-screw c to be fitted.

In practice the ink is deposited in the space between A and B by a dropper. The flow of ink between the nibs is regulated by turning the thumb-screw c until the proper adjustment is found. To facilitate thorough cleaning after use, the thumb-screw c can be removed and the ink-holder opened on the hinge d, as illustrated in Fig. 3.

I am aware that pens have been made heretofore with rigid nibs and with beveled marking-surfaces, also that ink-holding devices are common. I do not claim such broadly.

What I claim, and desire to secure by Letters Patent, is—

1. A pen with nibs which are each semicircular in shape on its transverse section at the point, the said nibs terminating in a marking-surface which is a circular plane.

2. A pen with rigid nibs which terminate in a circular plane marking-surface, said circular plane marking-surface being beveled to an angle of forty-five degrees with the longitudinal axis of the pen.

3. The combination in a fountain lettering-pen, of a pen-body with rigid nibs ending in a flat, beveled, circular marking-surface and an ink-holding device of sheet metal, fitted to the under side of the pen-body, with two flat opposing sides and flat bottom, the sides fitted over and close to the exterior edges of the pen-body and hinged at their upper ends on pins extending outwardly from the said pen-body and with their lower ends extending above the top of the pen-body and connected across and over the top of the pen-body by a set-screw and with the lower edge of the bottom part fitted closely into a transverse notch in the said pen-body; all in combination and for the purposes herein set forth.

In testimony whereof I have signed my name to this specification in the presence of two subscribing witnesses.

OCTAVE PAYZANT.
